US00D747596S

(12) **United States Design Patent**
Vestuti et al.

(10) **Patent No.:** US D747,596 S
(45) **Date of Patent:** ** Jan. 19, 2016

(54) **SHOE SOLE**

(71) Applicant: **Reebok International Limited**, London (GB)

(72) Inventors: **Ricardo Vestuti**, Providence, RI (US); **Kevin Leary**, Dedham, MA (US); **Mike Andrews**, East Falmouth, MA (US); **William McInnis**, Westwood, MA (US)

(73) Assignee: **Reebok International Limited**, London (GB)

(**) Term: **14 Years**

(21) Appl. No.: **29/479,405**

(22) Filed: **Jan. 15, 2014**

Related U.S. Application Data

(57) **CLAIM**

The ornamental design for a shoe sole, as shown and described.

DESCRIPTION

FIG. 1 is a bottom perspective view of a shoe sole showing our new design;

FIG. 2 is a front view thereof;

FIG. 3 is a rear view thereof;

FIG. 4 is a side view thereof;

FIG. 5 is another side view thereof;

FIG. 6 is a top plan view thereof; and,

FIG. 7 is a bottom view thereof.

The broken lines and unshaded areas within the broken lines depict environment and form no part of the claimed design.

1 Claim, 6 Drawing Sheets
